UNITED STATES PATENT OFFICE.

WILLIAM C. ZELLE, OF ST. LOUIS, MISSOURI, ASSIGNOR TO PLANTATION EQUIPMENT COMPANY, OF ST. LOUIS, MISSOURI, A CORPORATION OF MISSOURI.

TILLING-MACHINE.

1,084,918.

Specification of Letters Patent.

Patented Jan. 20, 1914.

Application filed June 17, 1912. Serial No. 704,037.

To all whom it may concern:

Be it known that I, WILLIAM C. ZELLE, a citizen of the United States, and a resident of the city of St. Louis and State of Missouri, have invented a new and useful Improvement in Tilling-Machines, of which the following is a specification.

This invention relates to tilling machines and more particularly to a drag or implement carrier for supporting implements in working position from a carriage or tractor.

It has for its principal objects to produce a device adapted for the attachment of agricultural implements of various kinds interchangeably; to provide for a universal adjustment and positioning of various implements in working relation and in various combinations; and to attain certain advantages which will hereinafter more fully appear.

The invention consists in the parts and in the arrangements and combinations of parts hereinafter described and claimed.

In the accompanying drawings which form part of this specification and wherein like symbols refer to like parts wherever they occur,—Figure 1 is a side elevation of a machine illustrating an embodiment of the invention; Fig. 2 is a top plan view of the drag and a portion of the supporting parallelogram frame; Fig. 3 is a side elevation of the parts shown in Fig. 2; Fig. 4 is a fragmentary section on the line 4—4 of Fig. 2, showing the parts on a slightly enlarged scale; Fig. 5 is a section on the line 5—5 of Fig. 4; Fig. 6 is a fragmentary top plan view of one of the transverse implement holder beams adjacent to the middle strut member; Fig. 7 is a side elevation of the parts shown in Fig. 6; Fig. 8 is a transverse vertical section through the implement holder beam in the region of the middle strut member; Fig. 9 is a top plan view of one of the movable implement holders; Fig. 10 is a section on the line 10—10 of Fig. 9; Fig. 11 is a side elevation of the parts shown in Figs. 9 and 10; Fig. 12 is a section on the line 12—12 of Fig. 10; and Fig. 13 is a section on the line 13—13 of Fig. 10.

The device may be arranged and adapted for attachment to a carriage or tractor of any desirable type, but for the purpose of illustration it is shown in connection with a tractor like that set forth in an application filed by me on April 1, 1912, Serial No.

687,929. The tractor shown is designed more particularly for "straddle-row" cultivation, but it is not limited to such use. It comprises a structural platform or body frame 1 mounted at one end on pedestal side frames 2, in which latter are located the propelling traction wheels 3. The opposite end portion of the platform or body frame is mounted on an auxiliary carrier frame 4, which in turn is supported on caster wheels 5 whereby the machine may be steered and turned. The specific construction and arrangement of the tractor by itself forms no part of the present invention and no further description thereof will be given in the present application except as to such parts that are necessary to the full understanding of the invention or enter into the combinations of the claims.

The implement carrier or drag frame is shown attached to the tractor through the medium of a hinged parallelogram frame which co-operates with the adjusting and raising and lowering device as fully set forth in a companion application Serial No. 704,036 filed herewith for a tilling machine.

The tractor is provided at its rear with brackets 6 near the top and bottom of the pedestal side frames 2. These brackets 6 are provided with bearings whose axes are in the same vertical plane. The upper and lower members 7 of the parallelogram frame are hinged at one end to these brackets 6 and at their outer ends to the vertical frame members 8, the vertical distance between the centers of the axes of the inner and outer pivots being the same.

The adjusting and raising and lowering device includes a yoke 9 pivoted at its inner end about the axis of the upper brackets 6 and having a swivel block 10 at its outer end. A nut 11 is rotatably mounted in the swivel block 10 and has a screw 12 working therethrough whose lower end is hinged about the axis of the pivot 8, which connects the upper parallelogram frame members 7 and the vertical members 8 thereof. The nut 11 is provided with a handwheel 13 for rotating it.

A rod 14 is pivoted at one end to the yoke 9 and its opposite end portion is telescoped within a hollow screw 15. The rod 14 is provided with a longitudinal slot 16 through which a pin 17 on the hollow screw 15 projects, so that the rod and screw are permitted

independent endwise movement but are prevented from rotating independently of each other. A spring 18 is coiled about the rod 14 between a shoulder at the outer end thereof and the end of the screw so as to hold the rod extended, its outermost position being limited by the pin 17 engaging the end of the slot 16. The screw 15 works through a nut 19 which is swiveled in a swivel support 20 having trunnions 21 journaled in bearings 22 on the carriage frame 1. The nut 19 may be rotated through the medium of any suitable driving mechanism which may obviously derive its power from the motor 15 which propels the tractor or any other source of power specially provided.

An operating lever 23 is connected to a clutch mechanism so that when the lever is moved in one direction the nut 19 is rotated 20 to move the screw and rod lengthwise in the proper direction to raise the parallelogram frame with the implement carrier or drag thereon, and when the lever is moved in the opposite direction the screw and rod are 25 moved reversely to lower the parallelogram frame and implement holder. This mechanism is shown and described in detail in the said other application Serial No. 704,036 filed herewith. Hence, no further description is necessary in the present application.

The drag as shown comprises an expandable and contractible frame hinged at one side to the parallelogram frame. This drag frame has side members composed of pairs 35 of spaced channels 24 placed with their webs vertical. The side members are hinged at one end on the lower cross bar 8 of the parallelogram frame and their outer end portions are connected by a cross bar 25. Yokes 40 26 are hinged to the cross bar 25 at one end and are provided at their opposite ends with cross members 27 having openings therethrough. Bolts 28 are hinged at one end on the upper cross bar 8 of the parallelogram 45 frame and are slidably fitted in the openings in the cross members 27. Portions of the bolts 28 are screw-threaded to fit nuts 29 swiveled in cross supports 30 on the yokes 26 at about the middle thereof. By turning 50 the nuts the bolts are moved lengthwise in either direction, thereby tilting the implement holder frame with respect to the parallelogram frame.

Pivottally mounted on bearings 31 secured 55 to the bottoms of the channel side members 24 of the implement holder frame are yokes 32 having toothed sectors 33 extending up between the channels. The teeth of these sectors are engaged by worm screws 34 journaled in brackets 35 on the top of said channel side members 24. The end portions of these worm screws are provided with polygonal faces 36 to be engaged by a suitable wrench for turning the worm screws. By 60 manipulating the worm screws the yokes are

rocked upon their pivots in either direction and are held at any desirable angle by said worm screws.

Transverse channel members 37 are arranged in pairs with their webs vertical and flanges outward. These members are riveted on counterpart bracket extensions 38 of said yokes 32; and riveted to the middle portions of the respective pairs of channels are strut members or castings 39 having end portions which are counterparts of the channel members so as to provide seats therefor. These members constitute implement holder beams. Slidably fitted over the channel members 37 are channel members 40. The flanges of the channel members 37 and 40 are provided with a multiplicity of perforations 41 adapted to register and receive locking pins hereinafter specified. The perforations 41 are arranged in like series on each side of the longitudinal center of the drag frame. The channel members 37 and 40 have their flanges extended laterally, the former at their outer ends and the latter at their inner ends, and riveted thereto are oppositely disposed substantially U-shape clips 42 in which right and left hand double screws 43 are swiveled. The screws have collars 44 located between the clips provided with polygonal faces for the reception of a wrench.

Locking members 45 have shank portions 45* threaded on the screws 43. They also have pins 46 adapted to enter the registered perforations 41 in the flanges of the channel members. Portions of the shanks 45* are made square so as to work in square notches in the flanges of the channel members in order to hold them from turning; while inwardly from said square portions they are rounded in order to permit them to turn after the square portions are moved clear of said notches. By rotating the screws the locking members are drawn toward each other to bring the projections 46 into the perforations 41 and thereby lock the sliding channel members with respect to the fixed ones. The sliding channel members 40 are connected at their outer ends by cross bars 47 having end plates 48 riveted to the web portions of said members. The implement carrier or drag thus comprises a rigid frame having extensible transverse members on which individual holders for the implements to be presently described are adjustably and interchangeably mounted.

The middle strut member 39 is provided with a central vertical opening 49 through which the shank of an implement may be passed. This opening 49 is preferably made to correspond with the contour of a shank 50 having flattened opposite faces whereby the shank is permitted endwise movement but prevented from rotating therein. The strut member is provided with a circular recess 51 having tapered side walls adapted 134

to receive a nut 52 having a beveled flanged end portion which is a counterpart of the recessed portion of the strut. A securing plate 53 having a central opening in which the circular middle portion of the nut fits is secured on top of the strut to hold the nut in place. The projecting upper portion 54 of the nut is provided with polygonal faces for the reception of a suitable wrench. The shank 50 is screw-threaded for a portion of its length to fit the nut, by the rotation of which latter in its seat said shank is raised and lowered.

Adjustable implement holders comprising members 55 having seat portions on opposite sides which are counterparts of the channel members are adapted to be detachably secured to the slidable channel members 40. These holders are provided with pivoted dogs 56 having pins or projections 57 adapted to enter the perforations 41 in the channel members to hold the implement holder in place. These dogs are provided with screws 58 adapted to bear against the top of the holder so that said dogs may be held with their pins 57 in the respective perforations of the channel members. These members 55 have rocking members 59 swiveled therein, the axis of the trunnions 59^c of said rocking members being at right angles to the channel members 37 and 40. The rocking member is provided with a sector 60 adapted to coöperate with a worm screw 61 journaled in brackets 62 on the member 55. This worm screw 61 is provided with polygonal faces 63 for the reception of a wrench.

Swiveled vertically in the rocking member 59 is a shank holder 64 having an opening therethrough whose sides are flattened to correspond with the flattened sides of the shank 50 of the implement. The shank holder is provided with a beveled seat adapted to receive the counterpart end portion of a nut 65. The nut 65 is held in place by a plate 66 having a central opening in which the middle portion of the nut is rotatably fitted. The upper portion 67 of the nut is provided with polygonal faces for the reception of a wrench. The rocking member is provided with a pair of half journal brackets 68 with which similar brackets 69 on the plate 66 coöperate. Journaled in these bearings is a worm screw 70 which meshes with a worm wheel 71 on the swiveled shank holder 64 whereby the latter may be rotated. This worm screw 70 is also provided with polygonal faces to receive a wrench.

By adjusting the channel members 40 with respect to the channel members 37, the implement carrier frame may be extended or contracted to different widths. The implement holders with the exception of the one mounted on the middle strut member 65 may also be placed at any desirable position

lengthwise of the channel members, and the implements set at various angles. The implement holder at the middle of the frame is, however, capable of vertical adjustment. This adjustment is all that is necessary as 70 the middle implement always travels along the middle of a furrow in a neutral position. It is different, however, with respect to the other implements on either side of the middle one, as they have to be set at various 75 angles in order to throw the dirt toward or away from the middle of the furrow, depending upon the nature of treatment.

Various combinations may be arranged by adjusting the implement holders. For example, in "barring-off" a plow may be mounted at either end of the holder frame so that the soil is only treated adjacent to the plants at the tops of the furrows without touching the middles. In another case a 80 double mold board plow may be mounted at the middle of the frame and on either side thereof may be arranged right and left hand plows for throwing a little dirt to the plants on opposite sides of the furrow, and at the 85 same time stirring the soil to kill the grass and weeds. Then, again, the soil may be stirred with shovel blades which may be arranged transversely to the direction of travel, in which case they do not throw earth to the plant, nor from it. Obviously, however, the shovels may be set so that the soil can be thrown toward or from the plant as desired. Also, in "laying-by," the dirt may be started at the middle of the furrow with 90 a double mold board plow, then throwing it to the plant, nor from it. Obviously, however, the shovels may be set so that the soil can be thrown toward or from the plant as desired. Also, in "laying-by," the dirt may be started at the middle of the furrow with 95 a double mold board plow, then throwing it closer to the plants by right and left hand mold board plows, and, finally, throwing the soil into the plant with sets of disks. So, too, the entire furrow may be cultivated 100 with disks. There may be a set of disks arranged to throw the dirt away from the plant at the top of the furrow, followed by a set of disks throwing the dirt from the middle toward the plants and these followed 105 by other sets of disks picking up the dirt and throwing it still nearer the plants, and, finally, sets of disks throwing the dirt into the plants. These and any other desirable 110 combinations may be effected owing to the 115 universal adjustment of the device.

The device is adapted for straddle row cultivation; and by mounting the holders on a tractor of the character set forth in said application, Serial No. 687,929, filed April 1, 1912, two entire furrows may be covered at the same time.

In order to facilitate setting the several tiltable and rotatable members of the machine accurately at the desired angle or position, graduated scales and coöperating indicators may be provided at convenient places. For example, as shown in Figs. 1, 2 and 3, the bolts 28 may be provided with a series of graduated lines 28^a in the region of 120 125 130

the respective cross members 27 of the yokes 26, so as to coöperate with either the upper or under sides of the members 27, as preferred. Preferably, the graduations are marked with suitable numbers ranging up and down from the middle or neutral line marked zero and being coincident with the side of the cross member 27 when the carrier frame is horizontal. Thus, it is easy to set the frame at the desired inclination up or down from its pivot end. The toothed sectors 33 on which the channel members 37 are mounted, are provided with semi-circular scales 33^a so as to be read in conjunction with marks 33^b provided on the top flanges of the side channel members 24 of the carrier frame to indicate the angle of the transverse channel members with respect to the side members. As described, the perforations 41 in the members 37 and 40 are arranged in the same spaced relation on each side of the longitudinal center of the carrier frame, and these lines of perforations may be used as scales. By this construction the extension members and the various implement holders may be placed symmetrically about the line of draft of the carrier frame, and when the adjustments of the implements are changed, by use of these perforations as scales, the various implements may be placed so that their resultant total resistance will coincide with the line of draft of the frame.

The rocking members 59 also are provided with arcuate scales 59^a on their side faces in coöperative relation to indicator marks 59^b on the adjacent top face of the implement holder frame 55; while the rotatory shank holder 64 has about its upper peripheral portion, preferably on the upper ends of the teeth of the worm gear 71, a series of graduations 64^a which may be arranged in two series on opposite sides, or, obviously, as a continuous annular series entirely girdling the member. These graduations 64^a are used in connection with indicator marks 64^b on the plate 66 which holds the nut 65 and shank holder 64 on the rocking member 59.

Obviously, the device admits of considerable modification without departing from the invention. Therefore, I do not wish to be limited to the specific construction and arrangement shown.

What I claim is:

1. In a machine of the character described, a traveling support, an implement carrier frame on said support, said frame comprising longitudinal members, rigidly connected spaced pairs of transverse implement holder beams pivotally mounted on said longitudinal members, and means for pivotally adjusting said pairs of implement holder beams and for holding them in adjusted position.

2. In a machine of the character described, a traveling support, an implement carrier

frame on said support, said frame comprising longitudinal members, rigidly connected spaced pairs of transverse implement holder beams pivotally mounted on said longitudinal members, said pairs of implement holder beams being provided with sectors whose operable portions are on a radius from the pivotal axes of said beams, and means on said longitudinal members engaging said sectors for pivotally adjusting said pairs of beams and for holding them in adjusted position.

3. In a machine of the character described, a traveling support, an implement carrier frame on said support, said frame comprising longitudinal members, rigidly connected spaced pairs of transverse implement holder beams pivotally mounted on said longitudinal members, means for pivotally adjusting said implement holder beams and for holding them in adjusted position, implement holders movably mounted longitudinally between said pairs of beams, said implement holders being supported at their opposite sides on the respective beams, and releasable means for locking said implement holders to said beams.

4. In a machine of the character described, a traveling support, an implement carrier frame on said support, said frame comprising longitudinal members, rigidly connected spaced pairs of transverse channel-shape implement holder beams pivotally mounted on said longitudinal members, and means for pivotally adjusting said spaced pairs of implement holder beams and for holding them in adjusted position.

5. In a machine of the character described, a traveling support, and an implement carrier frame on said support, said frame comprising longitudinal members, rigidly connected spaced pairs of transverse channel-shape implement holder beams pivotally mounted on said longitudinal members, said pairs of implement holder beams being provided with sectors, the operable portions of said sectors being on a radius from the pivotal axes of said pairs of implement holder beams, and means on said longitudinal members engaging said sectors for pivotally adjusting said pairs of implement holder beams and for holding them in adjusted position.

6. In a machine of the character described, an implement carrier comprising a frame having longitudinal members and transverse members pivoted thereon, means on said longitudinal members for actuating said transverse members and holding them in adjusted position, and separate implement holders mounted on said transverse members, said holders being adjustable for setting said implements at different angles with respect to said transverse members.

7. In a machine of the character described, an implement carrier comprising a

frame having longitudinal members and transverse members pivoted thereon, means on said longitudinal members for holding said transverse members in adjusted position, and separate implement holders mounted on said transverse members and having means for raising and lowering the implements and for setting them at various angles.

8. In a machine of the character described, an implement carrier comprising a frame having rigidly connected spaced pairs of transverse members mounted thereon and separate transverse members slidably mounted in coöperative relation longitudinally to said first mentioned members, releasable means for securing said transverse slidable and first mentioned members together, separate implement holders mounted on said transverse slidable members so as to move longitudinally between them, and means for releasably holding said implement holders in place.

9. In a machine of the character described, an implement carrier comprising a frame having transverse members arranged in rigidly connected spaced pairs, said connected pairs of members being pivotally mounted, means for holding said transverse members in adjusted position, and transverse members mounted on said first mentioned transverse members so as to move longitudinally thereof, and separate adjustable implement holders mounted on said transverse members so as to move longitudinally between them, said implement holders being capable of independent adjustment vertically and angularly.

10. An implement carrier for tilling machines comprising a frame, transverse members pivoted on said frame, said transverse members comprising rigidly connected spaced pairs of channels, additional transverse channels slidably mounted on said first mentioned channels, the flanges of said channels having perforations therein, releasable means for engaging the perforations in said flanges so as to lock said first and second mentioned channels together, separate implement holders mounted between said channels and having supporting portions fitted upon the flanges of said channels, and releasable means engaging the perforations in said flanges for locking said implement holders to the channels.

11. An implement carrier frame for tilling machines, comprising rigidly connected spaced pairs of longitudinal channel members, rigidly connected spaced pairs of transverse channel members, said pairs of transverse channel members being respectively secured to yokes, said yokes being pivotally mounted on brackets on the underside of said longitudinal members and having toothed sector portions projecting up between said longitudinal members, oppositely disposed

bearing brackets secured on top of said longitudinal members, and screws journaled in said bearing brackets and engaging the teeth of the sector portions of the respective yokes so as to effect the pivotal adjustment of said pairs of transverse channel members and hold them in adjusted position.

12. In an implement carrier for tilling machines, rigidly connected spaced pairs of transverse flanged implement holder beams, rigidly connected spaced pairs of extensible, similarly flanged beam sections slidable on said first-mentioned beams, the flanges of all of said beams being provided with a multiplicity of perforations arranged in aligned rows so that the perforations of adjoining flanges will register, and releasable locking means engaging through said perforations for securing said extensible beam sections in adjusted position.

13. In an implement carrier for tilling machines, rigidly connected spaced pairs of transverse flanged implement holder beams, rigidly connected spaced pairs of extensible, similarly flanged beam sections slidable on said first-mentioned beams, the flanges of all of said beams being provided with a multiplicity of perforations arranged in aligned rows so that the perforations of adjoining flanges will register, releasable locking means engaging through said perforations for securing said extensible beam sections in adjusted position, implement holders, slidably mounted between said pairs of beams and supported at opposite sides thereon, and releasable locking means on said implement holders engaging through said perforations in the flanges of said beams for securing the holders in adjusted position.

14. In an implement carrier for tilling machines, rigidly connected spaced pairs of transverse implement holder beams having outwardly disposed horizontal marginal flanges, rigidly connected spaced pairs of extensible, similarly flanged beam sections slidably mounted on the inner sides of said first-mentioned beams, the flanges of all of said beams being provided with a multiplicity of perforations arranged in aligned rows so that the perforations of adjoining flanges will register, a portion of the flange of one coöperating beam member being extended beyond the edge of the adjoining flange of the other member, and a releasable locking device on said flange extension adapted to engage through registered perforations in the adjoining flanges so as to secure said extensible beam sections in adjusted position.

15. In an implement carrier for tilling machines, rigidly connected spaced pairs of transverse implement holder beams having outwardly disposed horizontal marginal flanges, rigidly connected spaced pairs of extensible, similarly flanged beam sections

- slidably mounted on the inner sides of said first-mentioned beams, the flanges of all of said beams being provided with a multiplicity of perforations arranged in alined rows so that the perforations of adjoining flanges will register, a portion of the flange of one coöperating beam member being extended beyond the edge of the adjoining flange of the other member, a releasable locking device on 10 said flange extension adapted to engage through registered perforations in the adjoining flanges so as to secure said extensible beam sections in adjusted position, implement holders adjustably mounted between said pairs of beam members, said implement holders having counterpart opposite side portions slidably fitted on said beam members, and releasable locking devices on said implement holders adapted to engage 15 through said perforations in the flanges of said beam members for securing the holders in adjusted position.
16. The combination with an implement carrier for tilling machines, said carrier comprising rigidly connected spaced pairs of implement holder beams, separate implement holders mounted between said pairs of beams and slidably supported thereon, and releasable means for locking said implement holders to said beams, said implement holders each having a shank-receiving member swiveled vertically thereon, means for adjusting the shank vertically through said swiveled member, and means for tilting said 20 implement holder on an axis at substantially right angles to that of the swiveled shank receiving member and transversely to said implement holder beams.
17. In an implement carrier for tilling 25 machines, longitudinal frame members, rigidly connected spaced pairs of transverse implement holder beams pivoted on said longitudinal members, means for pivotally adjusting said pairs of implement holder beams and for holding them in adjusted position, the respective pairs of beams being connected at the middle by a strut member having a vertically adjustable implement holder, spaced pairs of extensible beam members 30 slidable on said first-mentioned beams, releasable locking means for securing said extensible beam members in adjusted position, and implement holders movably mounted between said extensible beam members, said implement holders being slidably supported at opposite sides on said extensible beam members, and releasable locking means for securing said last-mentioned implement holders in adjusted position.
18. In an implement carrier for tilling 35 machines, a plurality of spaced pairs of implement holder beams, pairs of similar beam sections slidably mounted on said implement holder beams, a plurality of implement holders independently adjustable upon said pairs of implement holder beams and said beam sections, releasable means for securing the said beam sections in their adjusted positions, and means on said implement holders adapted to support interchangeable implements, said means being operable to adjust said implements vertically and angularly.
19. In an implement carrier for tilling 40 machines, a plurality of spaced pairs of flanged beams, pairs of similar flanged beam sections slidably mounted upon said beams, implement holders independently adjustable upon said beams and said beam sections, releasable means for securing said beams and said beam sections in their adjusted positions, and means on said implement holders adapted to support interchangeable implements, said means being operable to adjust said implements vertically and angularly.
20. In an implement carrier for tilling 45 machines, a plurality of spaced pairs of implement holder beams, implement holders slidably mounted upon said pairs of beams, means for securing said implement holders in their adjusted positions and means on said implement holders adapted to support interchangeable implements, said means being operable to adjust said implements vertically and angularly.
21. In an implement carrier for tilling 50 machines, spaced pairs of beams, strut members connecting the respective pairs of beams, implement supports mounted on said strut members adapted to support implements, implement holders mounted on said beams and slidably adjustable thereon and means on each holder to adjustably support interchangeable implements.
22. In an implement carrier for tilling 55 machines, spaced pairs of beams, strut members connecting the respective pairs of beams, implement supports mounted on said strut members adapted to support implements, similar pairs of beam sections slidably mounted on said beams, strut members secured to the ends of said pairs of beam sections, implement holders mounted on said beams and said beam sections and slidably adjustable thereon, and means on each holder to adjustably support interchangeable implements.
23. In an implement carrier for tilling 60 machines, a carrier frame supporting a plurality of beams having a series of alined perforations arranged in the same spaced relations on each side of the line of draft of said carrier frame, implement holders slidably mounted on said beams and releasable means insertible in said perforations for securing said holders in their adjusted positions.
24. In an implement carrier for tilling 65 machines, a carrier frame, spaced pairs of beams mounted thereon, pairs of similar

- beam sections slidably mounted on said beams, said beams and beam sections being provided with a series of alined perforations arranged in the same spaced relation on each side of the line of draft of said carrier frame, implement holders slidably mounted on said beams and releasable means insertible in said perforations for securing said holders in their adjusted positions.
25. In an implement carrier for tilling machines, a carrier frame, a plurality of flanged beams mounted thereon, similar flanged beam sections slidably mounted on said beams, the flanges of both the beams and the beam sections having series of alined perforations adapted to register with one another and arranged in the same spaced relation on each side of the line of draft of said carrier frame, and releasable means insertible through registered perforations of said series for securing said beams and said beam sections in their adjusted positions.
26. In an implement carrier for tilling machines, a carrier frame, a plurality of flanged beams mounted thereon, similar flanged beam sections slidably mounted on said beams, the flanges of both the beams and the beam sections having series of alined perforations adapted to register with one another, each beam having a flange extension extended beyond the edge of the adjoining flange of the corresponding beam section, a releasable locking device having a cylindrical portion and a polygonal portion
- 35 mounted in a polygonal opening in said flange extension, said locking device having its polygonal portion engaged in said opening during the normal locking movement and its cylindrical portion engaged in said opening in its unlocked position, and means 40 for operating said locking device.
27. In an implement carrier for tilling machines, a carrier frame, a plurality of beams mounted thereon, a plurality of implement holders slidably mounted upon said beams, said beams having series of alined perforations in the same spaced relation on each side of the line of draft of said frame, means insertible in said perforations for securing said holders in their adjusted positions, means on said implement holders adapted to support interchangeable implements, said means being operable to adjust said implements vertically and angularly, and means upon said implement holders 50 adapted to show the relative positions of said implements, so that the implements on each side of the line of draft may be adjusted to the same degree and keep the resistance of all the implements on said frame 55 coincident with the line of draft.

Signed at St. Louis, Missouri, this 11th day of June, 1912.

WILLIAM C. ZELLE.
